FOOTSTOCK FOR CAM LAPPING MACHINES

Herbert S. Indge and George E. Hulbert, Westboro, Mass., assignors to Norton Company, Worcester, Mass., a corporation of Massachusetts

Original application August 21, 1936, Serial No. 97,232. Divided and this application May 27, 1937, Serial No. 145,074

5 Claims. (Cl. 82—31)

This invention relates to abrading machines, and more particularly to a footstock for supporting a rotatable work piece. This is a division of our copending application, Serial No. 97,232, filed 5 August 21, 1936.

One object of the invention is to provide a simple and thoroughly practical footstock for supporting a cylindrical work piece in an abrading machine, such as a camshaft lapping machine. A further object of this invention is to provide an improved footstock in which a footstock center is moved to and from a proper position by means of a toggle lever mechanism. Another object of the invention is to provide an improved footstock in which a fluid pressure actuated toggle lever mechanism is provided for moving the footstock center toward or from an operative position. Other objects will be in part obvious or in part pointed out hereinafter.

20 The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a sectional view through the improved footstock showing the toggle lever mechanism and the fluid pressure actuated drill mechanism therefor;

Fig. 2 is a cross sectional view through the footstock control valve, taken approximately on the line 2—2 of Fig. 1;

Fig. 3 is a longitudinal sectional view taken approximately on the line 3—3 of Fig. 1; and

Fig. 4 is a fragmentary horizontal sectional view, taken approximately on the line 4—4 of Fig. 1.

The improved footstock 10 has been illustrated in the drawing for rotatably supporting a work piece in a grinding or lapping machine, such as a camshaft lapping machine.

45 The footstock 10 supports a rotatable footstock spindle 11 which in turn carries a footstock center 12. The spindle 11 is journaled in bearings 13 and 14 within a hollow slidably mounted sleeve 15. The sleeve 15 is slidably keyed by means of 50 the key 16 within an aperture 17 in the footstock frame 10.

A fluid pressure actuated mechanism is providing for moving a footstock center 12 rapidly to and from an operative position to support a 55 rotatable work piece, such as a camshaft, within

the machine. This mechanism comprises a fluid pressure cylinder 20 having a slidably mounted piston 21 contained therein. The piston 21 is connected to one end of the piston rod 22, the other end of which is connected to a pin 23. 5 The central portion of the pin 23 is slabbed off on opposite sides so as to slide freely within an elongated slot 24 formed within an enlarged portion at the lower end of the piston rod 22. The pin 23 serves as a central pivotal connection between a pair of toggle levers 25 and 26. The other end of the toggle levers 26 is connected to the footstock frame 10 by means of a stud 27. The other end of the toggle levers 25 is connected by stud 28 with a slidably mounted sleeve 29 which slides within an aperture 30 within the sleeve 15. The sleeve 29 is held against rotation by means of a pin 31 carried by sleeve 15 and which rides within an elongated slot 32 in sleeve 29. A spring 33 is contained within the sleeve 29 15 and is interposed between the end of the sleeve 29 and the thrust collar 34.

When fluid under pressure is admitted to cylinder chamber 36, the toggle levers 25 and 26 are moved from full line positions 25 and 26 into the dotted line positions 25a and 26a (Fig. 1) which serves to move the sleeve 29 toward the right. This movement serves to move the sleeve 15 and footstock center 12 into an inoperative position.

In order readily to control the movement of the footstock center, a control valve 40 is formed integral with the cylinder 20. The valve 40 is preferably of a piston type and serves to control the admission of fluid under pressure passing through the pipe 41 to the cylinder. A control 25 lever 42 which is pivotally mounted on a stud 43 carried by a bracket 44 formed integral with the valve casing is connected by a stud 45 with a spool shaped head 46 carried on the end of a valve stem 47. Formed integral with the valve stem 40

47 are the valve pistons 51, 52 and 53. A valve chamber 54 is formed between the valve pistons 51 and 52 and a valve chamber 55 is formed between the valve pistons 52 and 53. In the position shown in Figs. 2 and 3, the valve piston 52 45 closes and prevents passage of fluid through the inlet pipe or port 41. When it is desired to cause the piston 21 to move upwardly to withdraw the footstock spindle 15 and center 12 to an inoperative position, the lever 42 is rocked in a clockwise 50 direction to shift the valve stem 47 toward the left (Fig. 2) to allow fluid under pressure passing through the pipe or port 41 to enter the valve chamber 55 and to pass through the passage 48 into the lower cylinder chamber 36 to cause the 55

piston 21 to move upwardly and thereby shift the toggle levers 25 and 26 from their full line position (Fig. 1) into dotted line positions 25a and 26a, thereby withdrawing the footstock center 12 to an inoperative position.

During the upward movement of the piston, fluid within the upper cylinder chamber 50 passes outwardly through the passage 49 into the valve chamber 54 and out through the passage 56 which is connected by a pipe (not shown) to return the fluid to a reservoir or source of supply.

Similarly, when it is desired to move the center 12 into an operative position, the lever 42 is moved in a counterclockwise direction to shift the valve stem 47 toward the right (Fig. 2) so that fluid under pressure passing through the pipe 41 enters the valve chamber 54 and passes through the passage 49 into cylinder chamber 50 to move the piston 21 downwardly into the position shown in Fig. 1, thereby shifting the toggle levers 25 and 26 from the dotted line positions 25a and 26a into the full line positions, as shown in Fig. 1.

During the downward movement of the piston, fluid within the cylinder chamber 36 exhausts through the passage 48 into the valve chamber 55 and out through the exhaust passage 56.

The operation of the improved footstock will be readily apparent from the foregoing disclosure. By the manipulation of the control lever 42 the footstock center 12 may be moved into and/or away from an operative position relative to the work piece. The footstock 10 is operatively adjusted along its supporting base so that when the toggle levers 25 and 26 are in a closed position, that is in a straight line position, it holds the footstock center 12 in operative engagement with the work piece, and the spring 33 will be under compression so that the footstock center is maintained in yielding engagement with the work piece during operation of the machine.

It will thus be seen that there has been provided by this invention apparatus in which the various objects hereinabove set forth together with many thoroughly practical advantages are successfully achieved. As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

We claim:—

1. A footstock for an abrading machine comprising a footstock frame, a movable footstock center, a slidable sleeve supporting said center, a fluid pressure piston and cylinder, said cylinder being fixedly mounted on said steadyrest frame, a pair of toggle levers which are operated

by said piston to move said sleeve and center to and from an operating position, and a control valve which is fixedly supported on the steadyrest frame to admit fluid under pressure to move the footstock center either toward or from an operating position.

2. A footstock for an abrading machine comprising a footstock center, a slidable sleeve, anti-friction bearings between the center and sleeve, a second sleeve slidably mounted within the first sleeve, a spring interposed between said sleeve, a fluid pressure piston and cylinder, a pair of toggle levers connected to said pistons, one of said toggle levers being connected to the frame, connections between the other toggle lever and said second sleeve, and means including a manually operable control valve to admit fluid under pressure to said cylinder to open or close said toggle levers so as to move the footstock center either toward or from an operative position.

3. A footstock for an abrading machine comprising a footstock frame, a slidably mounted sleeve supported therein, a rotatable work supporting center carried within said sleeve, a fluid pressure piston and cylinder operatively connected to move said spindle toward or from an operative position, and yieldable means interposed between the piston and cylinder and spindle yieldably to maintain the center in an operative position.

4. A footstock for an abrading machine comprising a footstock frame, a slidably mounted sleeve supported therein, a work center carried thereby, a slidable sleeve within said first named sleeve, a spring interposed between said sleeves, and means including a fluid pressure piston and cylinder and a control valve on said frame which are operatively connected to move said second sleeve to compress said spring and to move the spindle and center into yielding engagement with a work piece.

5. A footstock for an abrading machine comprising a footstock frame, a slidable sleeve supported therein, a footstock center carried by said sleeve, a second sleeve slidably mounted within the first sleeve, a spring interposed between said sleeves, a fluid pressure piston and cylinder, a vertically arranged fluid pressure piston and cylinder, a pair of toggle levers which are operatively connected between the piston and second sleeve yieldably to move the first sleeve and center into an operative position in yielding engagement with a work piece, and a manually operable control valve formed integral with said cylinder which is arranged to move the center to and from an operating position.
